United States Patent Office

Des. 230,643

Patented Mar. 5, 1974

230,643

AIRPLANE

Wilfred C. J. Garrard, Marietta, Henry R. Leslie III,
Atlanta, and Dallas M. Ryle, Jr., and Francis M.
Wilson, Jr., Marietta, Ga., assignors to Lockheed Air-
craft Corporation, Burbank, Calif.

Filed Mar. 13, 1972, Ser. No. 234,473

Term of patent 14 years

Int. Cl. D12—07

U.S. Cl. D71—1 N

FIG. 1

FIG. 2

FIG. 3

FIG. 4

FIG. 1 is a perspective view taken from below and to one side of an airplane embodying the present design;

FIG. 2 is a front elevation thereof with movable elements in alternate positions;

FIG. 3 is a top plan view thereof; and

FIG. 4 is a side elevation thereof.

We claim:

The ornamental design for an airplane, substantially as shown and described.
